UNITED STATES PATENT OFFICE.

RICHARD D. MURPHY, OF LA CROSSE, WISCONSIN.

HARNESS-SADDLE.

SPECIFICATION forming part of Letters Patent No. 663,920, dated December 18, 1900.

Application filed February 26, 1900. Serial No. 6,505. (No model.)

To all whom it may concern:

Be it known that I, RICHARD D. MURPHY, a citizen of the United States, residing at La Crosse, in the county of La Crosse and State of Wisconsin, have invented certain new and useful Improvements in the Construction of Harness-Saddles; and I do hereby declare the following to be a full, clear, and exact description of the invention, such as will enable others skilled in the art to which it appertains to make and use the same.

This invention relates to harness-saddles either for draft and driving or for single and double harness, the purpose being the provision of a device of the character aforesaid in which the padding will retain its shape and elasticity and obviate chafing and galling the animal.

For a full description of the invention and the merits thereof, and also to acquire a knowledge of the details of construction of the means for effecting the result, reference is to be had to the appended description and drawings hereto attached.

While the essential and characteristic features of the invention are necessarily susceptible of modification, still the preferred embodiment of the invention is illustrated in the accompanying drawings, in which—

Figure 1 is a vertical central longitudinal section of a harness-saddle constructed in accordance with the principles of this invention. Fig. 2 is a perspective view of a bur-piece having the padding and covering therefor in position. Fig. 3 is a top plan view of a bur-piece stripped. Fig. 4 is an edge view of the bur-piece.

Corresponding and like parts are referred to in the following description and indicated in all the views of the drawings by the same reference characters.

The harness-saddle in its general construction is of ordinary formation and comprises the tree or frame 1, of metal, the jockey 2, the pad, and the usual trimmings, including the check-hook 3 and terrets 4. The outline of the saddle will depend largely upon the purpose for which it is designed and upon the caprice of the manufacturer.

The invention deals more particularly with the pad, or, more properly speaking, the bur-piece forming the back of the pad, and this

bur-piece may be of any suitable material and is preferably molded into the required shape. Of the metals aluminium is preferred for the construction of the bur-piece because of its lightness and non-corrosive properties. It is contemplated to use papier-mâché or any fibrous material capable of being pressed or molded into the required shape. The bur-piece is provided with openings 5, 6, and 7 at intervals in its length and with a notch 8 at its inner end to clear the bur 9, to which the threaded shank of the check-hook 3 is attached. A plate 8^a underlaps the notched ends of the bur-pieces and supports the bur 9 and prevents injury to the inner covering 16 at the neck of the pad.

It is to be understood that a bur-piece is provided for each side or end portion of the saddle, and these bur-pieces are curved longitudinally and are widened transversely at a point intermediate of their ends. The central portion of the bur-pieces is thickened to correspond with the hollow portion at each side of the vertebra of the animal. By thickening the bur-pieces midway of their ends it is not necessary to provide excessively thick padding, and the latter may be more nearly uniform. The notch 8 and openings 5, 6, and 7 are formed simultaneously with the molding of the bur-pieces, thereby cheapening the construction and avoiding subsequent handling to bore or punch these parts. An oblong recess 10 is formed in the top side of each bur-piece and intersects the opening 6 and is adapted to receive the wings of the terret-bur 17, which is fitted therein. The burs a and b for the fastening-screws 11 and 12 are fitted in the openings 5 and 7 with their wings underlapping the bur-piece and preferably fitted in depressions formed in the bottom side thereof. The outer end of each bur-piece is reduced for a short distance, as shown at 13, to receive the flexible end pieces 14, to which the ends of the pad-covering are attached.

The padding 15 consists, preferably, of strips of felt or like fibrous material shaped to conform to the outline of the bur-piece and secured thereto and protected by the covering 16, which is secured at its longitudinal edges to the corresponding edge portions of the bur-piece in any manner found most con-

venient. This padding may consist of a single layer or two or more plies, according to the thickness of the material constituting the same. By using felt or like material the objections urged against filling of hair and similar loose material are wholly obviated and the padding is not likely to collect and produce welts, chafing, and galling.

After the bur-pieces have been covered 10 they are fitted to the end portions of the tree 1 and are secured thereto by the fastenings 11 and 12, the inner fastenings 11 passing through the tree and bur-pieces and the outer fastenings 12 through these parts and 15 the terminals of the jockey. The terret-burs 17 are placed in the openings 6 with their wings lying in the recesses 10 and are confined in their respective seats by the tree. The terrets 4 have their shanks screwed into 20 the terret-burs 17 in the ordinary manner.

The construction is exceedingly simple and minimizes the cost of manufacture and provides a harness-saddle which will maintain

its initial shape and prevent displacement of the padding and lessen the chances of producing sores, generally resulting from unequal distribution of pressure and the gathering of the padding in lumps and welts.

Having thus described the invention, what is claimed as new is—

A bur-piece for harness-saddles constructed substantially as herein shown and described, the same being formed of rigid material longitudinally curved and having its middle portion thickened and tapering toward the ends and widened intermediate of its ends on symmetrically-curved lines, and having a notch at its inner end and its outer end cut away upon its under side for a short distance, said bur-piece having a middle and end openings, substantially as specified.

RICHARD D. MURPHY.
